His Attorney

UNITED STATES PATENT OFFICE.

LEON CAMMEN, OF NEW YORK, N. Y., ASSIGNOR TO GENERAL ELECTRIC COMPANY, A CORPORATION OF NEW YORK.

MULTIPLE-FILAMENT INCANDESCENT LAMP.

1,419,816.

Specification of Letters Patent. Patented June 13, 1922.

Application filed April 15, 1918. Serial No. 228,629.

To all whom it may concern:

Be it known that I, LEON CAMMEN, a citizen of the United States, residing at New York city, in the borough of Manhattan, 5 State of New York, have invented certain new and useful Improvements in Multiple-Filament Incandescent Lamps, of which the following is a specification.

The object of my invention is to provide 10 a multiple filament lamp having a base of the usual bayonet type and suitable for use in any of the standard sockets commonly used on automobiles and provided with a simple means operable by the fingers, if 15 necessary, for putting a reserve filament into circuit. A further object is to provide for lamps of this type a base which can be easily and cheaply manufactured from stamped or pressed parts and which costs very little 20 more than the standard bases now in use. Another object is to improve and cheapen the construction of multiple filament lamps suitable for use in standard sockets.

To these ends I provide the base with 25 metal clips of such a form that they can be stamped out in large quantities at a very low cost and mounted on the base with very little expense in addition to that of mounting the usual terminals, and connected to 30 the reserve filament in such a way that whenever desired the reserve filament can be put in circuit by closing the circuit through the clips, preferably by grasping and pulling from between the clips a strip of insulation, 35 such as fiber or paper, which normally holds the clips apart. The strip of paper can be pulled out with the fingers, no special tools or expert manipulation being required.

My invention will best be understood from 40 the accompanying drawing in which merely for purposes of illustration I have shown one of the various forms in which it may be embodied and in which Fig. 1 is a phantom view in perspective of a lamp embodying one 45 form of my invention; Fig. 2 is a longitudinal section of the base along the line 2-2; Fig. 3 is a longitudinal section of the base along the line 3-3; and Fig. 4 is a diagram of the filaments and the circuits.

50 In the particular form of lamp illustrated in the drawing the bulb 10 contains two filaments 11 and 12 which have their adjacent inner ends connected to a lead 13 and the outer ends to leads 14 and 15. The lamp has 55 a bayonet base 16 consisting of a metal shell

with an insulating web 17 having a flat end with a recess or opening 18 in it. A circuit terminal 19 of the usual form is connected through the lead 13 to the adjoining ends of the filaments 11 and 12, and the other terminal 20 is connected to the outer end of the filament 11. With the connections just described, the filament 11 will be lighted when the lamp is inserted in the socket.

In order that the reserve filament 12 may 65 be brought into circuit whenever desired I provide means adapted for manipulation by the fingers for connecting the outer end of the filament 12 to terminal 20 to put the reserve filament 12 into circuit. The particu- 70 lar form of means illustrated in the drawings comprises two spring clips 21 and 22 mounted on the insulating web 17 between the terminals 19 and 20 and projecting into the central recess 18 by which they are pro- 75 tected. These spring clips are normally separated by a strip 23 of fiber, paper, or any other suitable insulating material. This strip projects from the base far enough so that the end can be seized and the insulating 80 strip withdrawn whenever desired. The clip 21 is electrically a part of the terminal 20, this result being accomplished by spreading the solder 24 to bridge the gap between the terminal and the clip when the lead 15 is 85 soldered to the terminal.

When the lamp is first inserted in the socket with the insulating strip 23 in the position shown in Fig. 1, the filament 11 is lighted. The reserve filament 12 can be in- 90 serted in the circuit merely by withdrawing the insulating strip 23, whereupon clips 21 and 22 spring together and establish a circuit from the terminal 19 through the filament 12 to the terminal 20. The driver of 95 the automobile can withdraw the strip 23 with his fingers, so that the reserve filament can be put into circuit without the use of tools and with very little trouble.

It will be seen that I provide a multiple 100 filament lamp with a standard bayonet base and a reserve filament which can be put into circuit without the use of tools or the manipulation of small or delicate parts. The clips 21 and 22 can be stamped out in large num- 105 bers at a very low cost and can be set in the web 17 of the base at the same time and in the same manner as the terminals 19 and 20, so that the additional expense is very slight. The metallic connection between the 110

terminal 20 and the clip 21 is made at practically no extra expense when the lead 13 is soldered to the terminal 19.

The conducting connection between the terminal 20 and the lead 14 can be established in other ways than by the withdrawal of the insulating strip 23 and I therefore do not wish to be restricted to the precise arrangement disclosed, but intend to cover all 10 modifications within the scope of the annexed claims.

What I claim as new and desire to secure by Letters Patent of the United States, is:—

1. An incandescent electric lamp having 15 two supply terminals and two filaments, one permanently connected in circuit with said terminals and the other normally kept out of circuit, and means comprising cooperating contacts and a removable insulating member 20 between said contacts for holding them separated and rendered operative by the removal of said insulating member from between the contacts to close the circuit through said auxiliary filament.
2. A combination with an incandescent electric lamp having a main filament of an auxiliary filament normally out of circuit, and means comprising cooperating contacts and a removable strip of insulation between 30 said contacts and responsive to the removal of said strip of insulation for connecting said auxiliary filament in circuit.
3. An incandescent electric lamp having two supply terminals and a main filament connected thereto, an auxiliary filament with one end connected to one of said terminals, a third

terminal for the other end of said auxiliary filament, and an electrical bridge between said third terminal and one of the other terminals normally held open by a strip of 40 insulation removable at will to close said bridge and connect said auxiliary filament into circuit.

4. In an incandescent lamp a base having a flat end with a central recess therein, a 45 main contact mounted on said end and having electrically connected to it a spring clip projecting into said recess, a cooperating spring clip mounted on said base to project into said recess and normally held out of 50 contact with the other spring clip by insulation readily removable by the fingers, a reserve filament connected to said cooperating spring clip and said main contact, a second main contact mounted on the end of 55 said base, and a main filament connected to said main contacts.

5. A base for a multiple filament lamp comprising a cylindrical web having a recess in one end, two main contacts mounted on 60 said end on opposite sides of said recess, a pair of spring clips mounted on said end opposite each other and between said main terminals to project into said recess and biased to move into contact with each other, and 65 a strip of insulation between said clips for holding them separated and having its end projecting to permit it to be readily seized and removed from between said clips.

In witness whereof, I have hereunto set 70 my hand this 12th day of April, 1918.

LEON CAMMEN.
